UNITED STATES PATENT OFFICE.

ARMIN ROSENBERG, OF MILWAUKEE, WISCONSIN.

PRACTICE GOLF BALL.

Application filed June 28, 1924. Serial No. 722,930.

To all whom it may concern:

Be it known that I, ARMIN ROSENBERG, a citizen of the United States, residing at Milwaukee, county of Milwaukee, and State 5 of Wisconsin, have invented new and useful Improvements in Practice Golf Balls, of which the following is a specification.

This invention relates to game equipment and more particularly to a novel practice 10 ball for use in the game of golf.

Soft practice balls have heretofore been made on tubular knitting machines, short sections of tube being filled with cotton batting or other suitable stuffing and the ends 15 of such tubular sections being drawn together by draw-strings to complete an article of a roughly spherical form. Such articles, however, are not perfectly spherical, but are puckered at their polar portions 20 so that they neither look nor act like standard golf balls.

It is the primary object of this invention to provide a practice golf ball resembling as closely as possible a standard golf ball such 25 as can be used in play. I have found that it is possible to crochet or knit a cover for a practice ball in true spherical form by making a plurality of rounds of interlocked stitches, and by adding or subtracting 30 stitches to successive rounds as may be necessary to form or shape the article in the course of the crocheting or knitting operation. The resulting cover is wholly seam- 35 less and may be made in true spherical form. Furthermore, the casing will have a tendency to retain and resume its natural spherical form under the expansive force of a body of cotton batting or the like under a slight compression within said casing as a 40 core therefor.

More particularly stated, therefore, it is the object of this invention to produce a soft practice golf ball having a seamless spherical cover, preferably of crocheted or knitted 45 construction and shaped in the process of manufacture so as to require no puckering or draw-strings to close it at its ends.

In the drawings:—

Figure 1 is a side elevation of a practice 50 ball embodying this invention.

Figure 2 is a detail view in plan of a portion of a crocheted cover shortly following the initiation of the operation of forming such a cover.

Figure 3 is a detail view in perspective 55 of a partially completed cover in readiness to receive its internal stuffing or core.

Figure 4 is a view similar to Figure 3 showing the core or stuffing in place within the partially completed cover. 60

Like parts are identified by the same reference characters throughout the several views.

It is very desirable that the completed practice ball show no seams, both for the sake 65 of appearance and for the more important reason that in order to serve its purpose and the function for which it is intended, it must resemble as exactly as possible a standard ball, so that persons becoming 70 used to striking the practice ball will find that the standard ball looks natural to them.

For the above reasons, and because the article can be made cheaply and economically, I prefer to crochet the cover for the 75 practice ball. The crochet work starts in spiral fashion as indicated in Figure 2, and the worker will shape the cover in the course of the crocheting operation. At first the work will be flat, but after the first 80 few rounds of stitching the operator will be employing fewer stitches than would be necessary to keep the work flat, commencing the shaping operation in a well-known manner. The shaping will be done in the usual 85 way in which caps and other articles of clothing are shaped in the course of being crocheted or knit.

When the spherical cover A is about three-quarters finished, as shown in Figure 90 3, the operator will fill or stuff it with any suitable material B, such as cotton waste, scraps, or the like. In actual practice, I have found that fibrous cotton or wool bat- 95 ting are excellently suited for use as a core.

Figure 4 shows the partially completed cover stuffed and in readiness for the completion of the crocheting operation. It would be possible to use a draw-string to bring the cover together and thereby to 100 compress the stuffing or core B. This, however, would pucker the cover and would not result in the production of a perfectly spherical practice ball, and accordingly I prefer to complete the cover by a continuation 105 of the crocheting operation already described. In each successive turn, the operator will use fewer stitches, until ulti-

mately a single stitch will close the top of the spherical cover, leaving the article completely in the form of a sphere.

While it is immaterial, in a broad sense, what the size of the completed article may be, it is nevertheless very much preferred for the reasons already stated, that the article shall be of substantially identically the size of a standard golf ball. The experienced operator will readily learn to crochet in such a manner as to make practice balls of standard size. This involves not only the number of stitches on each turn, but also involves the closeness with which the individual stitches are drawn and the size of yarn used. The spaces between the individual stitches closely resemble the small indentations with which a standard golf ball is provided and, if mercerized yarn be employed in the crocheting of the cover A, the resemblance will be heightened. Mercerized yarn has a gloss which makes the crocheted cover very closely resemble in color and texture a standard ball with the ordinary whitened finish.

In a preferred construction of my novel practice ball as disclosed herein, the strand of yarn designated at C will be continuous throughout the cover. In other words, I prefer to avoid knotting or piecing the strand, because a knot if unskillfully made, might result in destroying the otherwise perfectly spherical contour of the cover.

As indicated above, the size of the yarn employed has a bearing on the resulting size of the cover. In practice I have successfully used No. 3—2 mercerized white cotton yarn and have found the same to be satisfactory. I recognize, however, that other sizes of yarn might be employed if a different character of crochet stitch were used.

A ball made in accordance with the disclosure herein can be used indoors in limited quarters without danger, and although it

will be flattened by the impact of a club, it has a strong tendency to resume its original spherical form.

It will, of course, be understood that in the course of the completion of the crocheting or knitting operation by means of which the cover A is shaped during its formation, the individual stitches will be drawn or, in other words, subjected to additional tension in such a way as to place the core under slight compression. The compressed core tends to maintain the cover in its original truly spherical form and while no considerable degree of tension is used and no great compression results, nevertheless it is preferred that the article be constructed as indicated.

The fact that the cover is seamless and has no draw-string, greatly increases its life since, it has been found that in practice the draw-string may become broken and any stitching utilized to unite the seams may likewise become broken or torn from the seams to permit the cover to become ripped open.

I claim:

1. As a new article of manufacture, a ball including a core of fibrous material and a spherical casing compacting said material and formed integrally thereabout, said casing comprising a series of stitches in an ellipsoidal helical path and individually under tension, whereby said cover is shaped during manufacture and closely and smoothly embraces said core without puckering.

2. The method of constructing a ball having a fibrous core, such method including the crocheting of a cover in a continuous series of stitches in an ellipsoidal helical path about said core, the stitches made in closing the cover about the core being under such tension as to compact the core in spherical form within the cover.

ARMIN ROSENBERG.
